UNITED STATES PATENT OFFICE.

CHARLES A. GRAY, OF KANSAS CITY, KANSAS, ASSIGNOR TO BERTRAM W. BOXMEYER, OF KANSAS CITY, MISSOURI.

EMERGENCY-VALVE FOR SPRINKLER SYSTEMS.

No. 882,822.

Specification of Letters Patent. Patented March 24, 1908.

Application filed July 12, 1907. Serial No. 383,527.

To all whom it may concern:

Be it known that I, CHARLES A. GRAY, citizen of the United States, residing at Kansas City, in the county of Wyandotte and State of Kansas, have invented certain new and useful Improvements in Emergency-Valves for Sprinkler Systems, of which the following is a specification.

This invention relates to emergency valves for automatic sprinkler heads, and my object is to produce a device of this character whereby the water of an overhead sprinkler system can be quickly and easily cut off in the event that the plug is blown out or knocked off, it being well known that the escape of water from such cause frequently results in a great damage to goods in stores and warehouses equipped with such system.

A further object is to produce a device of this character which can be easily and quickly secured in position on any of the approved types of sprinkler heads in use.

A still further object is to produce a device of this character of simple, strong, durable, and cheap construction.

With these objects in view the invention consists in certain novel and peculiar features of construction and organization as herein-after described and claimed; and in order that it may be fully understood reference is to be had to the accompanying drawing, in which—

Figure 1, is a central vertical section of a sprinkler head equipped with a valve embodying my invention. Fig. 2, is a front view of the same. Fig. 3, is a side view of a modified construction of the valve.

In the said drawings, 1 indicates the tubular portion of the sprinkler head for attachment to the service pipe, not shown, 2 is the usual arch formed integral with and bridging such tubular portion and provided at its upper end with a perforated distributing cap 3 of the usual type. The drawings illustrate the head in the condition it is in after the plug has blown out or has been knocked off. The emergency valve for closing the upper end of the tubular portion is constructed as follows:—4 is a bar provided with a depending lug 5 and a socket 6 in its underside contiguous to said lug, and said socket is equipped with a rubber, leather or other compressible washer 7 of somewhat greater diameter than the bore of the tubular portion.

Projecting upward from the bar above the 55 socket is a pair of ears 8, and one or more pins 9, the ears of the construction shown in Figs. 1 and 2 being forward of the center of the tubular portion, while in the construction shown in Fig. 3, they are rearward of said 60 center. Pivoted to between the ears at 10 is a lever 11 provided at its upper edge with laterally projecting wings 12 and depending from said lever are one or more pins 13, the type of construction shown in Fig. 1 embodying a pair of pins 9 and 13 respectively, projecting upward from the bar 4 and downward from lever 11.

In the construction shown in Fig. 3, the bar 4 is equipped with a bail 14, for engagement with one of a series of notches 15 formed in the upper end of lever 11. In both constructions an expansive spring 16 is employed for the purpose of forcing the free or outer end of the lever upward from the bar, 75 said springs being mounted on pins 9 and 13 to avoid any possibility of accidental dislodgment. In the construction shown in Fig. 1, the other pair of pins is likewise engaged by a similar spring 17 which co-operates 80 with spring 16 in forcing the lever upward at its outer end, whereas in Fig. 3, the bail 14 when engaged with one of the notches 15 tends to prevent such upward movement of the lever, and in both constructions the opposite end of the bar is preferably provided with a hole 18 for convenience in suspending it from a hook or other support, not shown, when not in use.

In Fig. 2, the loop or arch of the head is of 90 the type in most common use, though said figure by dotted lines indicates the form of a different head used to a considerable extent in overhead sprinkler systems, it being noted that in the latter construction the upper portion of the arch is contracted so as to barely exceed in span the width of the lever plus that of the flanges 12.

Assuming that the head has blown out or has been knocked off and water under pressure spouts up through the head, any one by grasping the handle end of the attachment and pressing the lever downward toward the bar can slip the attachment through the arch until arrested by the contact of lug 5 with the 105 tubular portion 1, this action disposing the washer directly over the upper end of the tubular portion. As this is accomplished

the pressure on the handle is removed and the spring or springs force the lever upward until it bears firmly against the upper portion of the arch, the spring or springs thus serving to clamp the washer firmly down upon the head and arrest the flow of water. With the construction shown in Fig. 3, the same action is performed except that the device is slipped into position when the lever is raised and then the latter is pressed downward until it engages the upper end of the head at a point forward of the pivotal point of connection of the lever with the bar, it being held in this position by swinging the bail over the free end of the lever until it engages one of the notches 15, it being understood that by having a plurality of such notches, a variation in the height of the arch is accommodated. In the event that the head is of the type shown in full lines Fig. 3, no lateral adjustment of the valve is necessary because it fits snugly between the side portions of the arch, whereas should the arch be wider at its lower end such lateral adjustment might be necessary if it were not for the fact that the laterally projecting wings of the lever fit snugly in the contracted upper portion of the arch and therefore make it impossible for the valve to be slipped into position without the proper incidental registration of the washer with the tubular portion of the head.

From the above description it will be apparent that I have produced an emergency valve for automatic sprinkler heads, possessing the features of advantage enumerated as desirable, and I wish it to be understood that I do not desire to be restricted to the exact details of construction shown and described as obvious modifications will suggest themselves to one skilled in the art.

Having thus described the invention what I claim as new and desire to secure by Letters Patent, is:

1. A valve for sprinkler heads, comprising a bar provided at one side with a compressible washer, a second bar pivoted to the first out of alinement with the axial center of such washer and at the opposite side of the first-named bar from the said washer, and provided at its free end and opposite side from the first-named bar with notches, a spring interposed between the bars to press their free ends apart, and a pivoted bail carried by the first-named bar and adapted to fit over

the free end of the other bar and engage one of its notches.

2. The combination with a sprinkler head, comprising a tubular portion and an arch bridging the bore thereof, of a valve, comprising a bar to project through such arch and equipped at its lower side with a compressible washer to bridge the bore of said tubular portion, and a lever pivoted to said bar, out of alinement with the center of the bore of the tubular portion.

3. The combination with a sprinkler head comprising a tubular portion, and an arch bridging the bore thereof, of a valve comprising a bar to project through said arch and equipped at its lower side with a compressible washer to bridge the bore of said tubular portion, and with a depending lug to engage said tubular portion to prevent the bar being slipped too far through the arch, and a lever pivoted to said bar, out of alinement with the center of the bore of the tubular portion.

4. The combination with a sprinkler head, comprising a tubular portion and an arch bridging the bore thereof, of a valve comprising a bar to project through such arch and equipped at its lower side with a compressible washer to bridge the bore of said tubular portion, a lever pivoted to said bar, out of alinement with the center of the bore of the tubular portion, and means engaging the bar and lever to clamp said parts respectively firmly against the upper end of the tubular portion and the upper part of the arch.

5. A valve for sprinkler heads, comprising a bar provided at one side with a compressible washer, a second bar pivoted to the first out of alinement with the axial center of such washer and at the opposite side of the first-named bar from the said washer, and provided at its free end and opposite side from the first-named bar with notches and at the same side but opposite end with laterally projecting wings, a spring interposed between the bars to press their free ends apart, and a pivoted bail carried by the first-named bar and adapted to fit over the free end of the other bar and engage one of its notches.

In testimony whereof I affix my signature, in the presence of two witnesses.

CHARLES A. GRAY.
